UNITED STATES PATENT OFFICE.

JEFFERSON D. POTTS, OF ST. LOUIS, MISSOURI.

NON-PINCHING ATTACHMENT FOR LASTS.

1,283,295.

Specification of Letters Patent. Patented Oct. 29, 1918.

Application filed May 29, 1918. Serial No. 237,355.

To all whom it may concern:

Be it known that I, JEFFERSON D. POTTS, a citizen of the United States, residing at St. Louis, in the State of Missouri, have invented certain new and useful Improvements in Non-Pinchng Attachments for Lasts, of which the following is a specification containing a full, clear, and exact description, reference being had to the accompanying drawings, forming a part hereof.

My invention relates to an improvement in shoe-lasts, and it consists in the novel construction and arrangement of parts herein-after fully described and claimed.

Heretofore, in the manufacture of shoes upon the various machines which hold the work upon lasts, the construction has been such that the jack-stand pin and its metallic thimble have accidentally caught the material of the quarters and the lining thereof between said metallic parts and "pinched" one or both of them, and have in many cases, actually cut the material of the lining and the leather quarters, in such a way as to greatly damage them and require replacement of the parts at considerable expense.

The object of my invention is to provide such an improved construction of the shank or ankle of the last that the jack-pin cannot pinch, cut or damage the material of the shoe during the various steps of manufacture.

In the drawings,

Figure 1 is a side-elevation of a shoe mounted upon a last and jack-stand, and having my invention applied to said last.

Fig. 2 is a vertical section, taken on the line 2—2 of Fig. 1.

Fig. 3 is a vertical transverse section of the parts of the last and jack-stand shown in Fig. 2, enlarged somewhat.

Fig. 4 is a similar view, showing a modification.

Fig. 5 is an elevation of a further modification.

Fig. 6 is a rear elevation of a portion of the ankle of a last having my invention applied thereto, and

Fig. 7 is a diagrammatic plan view of the cushion-leather, thimble, and my anti-pinchng construction of the ankle of the last, and a piece of material, to illustrate the operation of my invention upon the material.

The numeral 1 designates the usual jack-stand; 2 the common pin thereof, and 3 the metallic thimble which is always seated in

the heel of the last and provided with the usual end-flange 4 to assist in taking the end-thrust of the said jack-stand pin.

Heretofore, the ankle of the last has had 60 the flange of said thimble flush with a cushion of leather 7 fixed by cement or glue on the seat of said ankle, which has permitted the material of the shoe to be accidentally caught and damaged between said flange 4 65 and the said pin, in the operation of placing the last carrying the shoe in position upon said jack-stand.

In carrying out my invention I place upon the seat 6 of the last-ankle either underneath 70 or exterior of the usual cushion 7, (when it is desired to apply my invention to the lasts in common use) an additional cushion, or a cushion 8 having an annular or circular recess 9 that is of such diameter that when the last is placed upon the jack-stand the pin 2 thereof will be cleared because of a considerable space or an annular space surrounding said pin, and extending such a distance outwardly beyond the outer face of the said 75 flange 4 of said thimble 3 that under the ordinary circumstances of the work with the last it will be impossible for the shoe lining or shoe material to be pushed into the said thimble by the said jack-pin and be 80 "pinched" or cut between the said pin and said flange of said thimble, but said material (if it should at all be caught by said pin) will be pushed a little way only into the said annular recess 9, and no damage will 85 be done to said material.

Referring to Fig. 2, the numeral 11 indicates the leather quarters of the shoe 12, while the numeral 14 designates the lining quarters.

In all the figures the numeral 15 designates the last.

In Fig. 4 I have shown a single cushion layer 8, having said annular or circular recess formed in it, and placed directly upon 100 the seat of the last ankle, as should be done in manufacturing new lasts; while in several other views I have shown the cushion in two layers, the outer one having my recess 9 in it, and which course may be followed 105 whether the last be new or old at the time of application of my invention thereto.

In Fig. 5 I have shown my improved recessed outer cushion 8 applied to a small-size last, the seat of which is too narrow to 110 permit me to cut the said annular or circular recess in it without weakening the angle too

much, and in such a case I propose to make the said outer recessed cushion layer wider than the inner layer 7, so that (as there shown) the opposite edges of said recessed layer project a distance beyond the edges of the said inner layer, and thereby preserve a sufficient body of the recessed cushion at the sides of the thimble 3 to withstand the pressure imposed by the jack-stand during use of the last.

However, in making new lasts of the smaller sizes the thickness of the ankle can be increased while the wood of the ankle is being fashioned, as may also its height; thereby doing away with the necessity of the inner layer 7, and locating the flange 4 of said thimble flush with the wood seat 6 of the last, as shown in Fig. 4.

In the operation of my invention, referring to Fig. 7, it will be seen that the shoe-material 14, when it is engaged accidentally by the pin of the jack-stand passing into the

flanged mouth of said thimble 3, will push said material laterally into said annular recess 9 surrounding said pin, without reaching or coming into contact with the flange 4 or any part of said thimble; and hence said shoe material will not be cut or damaged by said parts.

What I claim is:

A shoe-last having the usual flanged-thimble in its ankle portion, and a cushion having an annular recess of greater diameter than the diameter of the bore of said thimble, and placed on the outer end or seat of said ankle portion, exterior of said flange.

In testimony whereof, I have signed my name to this specification in presence of two subscribing witnesses.

JEFFERSON D. POTTS.

Witnesses:

FRANCES HOOVER ROSENBAUM,
JOHN C. HIGDON.
